Primary Examiner—Alan P. Douglas*Assistant Examiner*—S. Snapp*Attorney, Agent, or Firm*—Beveridge, DeGrandi, Weilacher & Young**[57] CLAIM**

The ornamental design for belt display device, shown.

DESCRIPTION

FIG. 1 is a top plan view of the display device;
FIG. 2 is a bottom plan view of the same device;
FIGS. 3 and 4 are opposite side views of the same device;

FIG. 5 is a front end view of the same device with the main surface thereof held horizontal;

FIG. 6 is a rear end view of the same device, with the main surface thereof held horizontal; and,

FIG. 7 is a front perspective view of the same device, in which the positions of belts being displayed is indicated. The dashed line representations of belts as shown in FIG. 7 are for illustrative purposes only and do not form any part of the claimed design.
